Gloria Fuentes **CLAIM**

The ornamental design for a medical injector pen, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a medical injector pen with the cap attached, in accordance with the present invention, in which the color of the pen cap and body, the color of the dosage knob, and the color of the dosage window bezel and actuator button all form part of the design. The color of the pen cap and body is Pantone 538C, the color of the dosage knob is Pantone 2766C, and the color of the dosage window bezel and actuator button is Pantone 272C;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof;

FIG. 7 is a bottom plan view thereof;

FIG. 8 is an enlarged fragmentary view of the encircled portion labeled as "8" in FIG. 2.

FIG. 9 is an enlarged fragmentary view of the encircled portion labeled as "9" in FIG. 3; and,

FIG. 10 is an enlarged fragmentary view of the encircled portion labeled as "10" in FIG. 4.

Diagonal lines on the cartridge holder indicate transparency.
